HAIR WAVING APPARATUS

Platon Constantine, New York, N. Y.

Application March 31, 1936, Serial No. 71,832

4 Claims. (Cl. 132—33)

This invention relates to improvements in hair waving apparatus and more particularly to a combined hair clamp and winding rod.

When arranging a strand of hair for the formation of a Croquignole style wave during a permanent hair waving process, it is the practice to flatly wind the hair upon a winding rod and then mount the winding rod upon a clamp and scalp protector for enabling the operator to impart a final winding of the wound hair to tension the same to give the hair the necessary stretch which is essential for the formation of a perfect curl. The apparatus now in use with which I am familiar, does not permit of the full winding of the strand of hair upon the winding rod, due to the thickness of the clamp and scalp protector, and the fact that after the winding rod is associated with the clamp, the same is spaced a considerable distance from the scalp where it remains during the heat treatment operation. Such practice causes that portion of the strand of hair between the scalp and the winding rod to remain straight after the formation of the wave which is imparted to that portion of the strand of hair which was fully wound upon the winding rod. It is therefore one of the main objects of this invention to provide a method of hair waving by which substantially the entire length of a strand of hair may be tightly wound upon the winding rod to be subsequently waved by the application of the solutions and heat treatment which usually follow the winding operation.

Another object of the invention resides in a hair clamp which includes a collapsible pin to which one end of a winding rod may be releasably anchored to permit the actuation of the winding rod by an operator for imparting the final tension or stretch to the wound hair, and which pin may be swung to a collapsed out of the way position after the winding rod has been turned to wind thereon the remaining portion of the strand of hair which permits the wound strand of hair to seat against the base of the clamp subsequent to the application of the heating element of a permanent waving machine.

Another feature of the invention is to provide an improved hair winding apparatus of the above mentioned character which may be expeditiously manipulated by an operator during a permanent hair waving process and which does not exceed in cost of manufacture, that of the apparatus now used for a like but not as efficient purpose.

With these and other objects in view, the invention resides in the certain novel construction, combination and arrangement of parts, the es-

sential features of which are hereinafter fully described, are particularly pointed out in the appended claims, and are illustrated in the accompanying drawing, in which:

Figure 1 is a perspective view of my improved hair winding apparatus illustrating the manner in which the free end and scalp end of a strand of hair is held clamped subsequent to the initial winding operation.

Figure 2 is a perspective view of the apparatus showing the strand of hair in a wound condition and about to receive its tensional stretch.

Figure 3 is an end elevational view showing the position of the winding rod after the tensional stretch has been imparted to the wound strand of hair.

Figure 4 is an end elevational view showing the strand of hair fully wound with the heating element in position thereover.

Figure 5 is an enlarged detail vertical sectional view on the line 5—5 of Figure 3.

Figure 6 is a horizontal sectional view on the line 6—6 of Figure 5.

Referring to the drawing by reference characters, the numeral 10 designates a combined clamp and scalp protector which includes a relatively thin rectangular shaped base 11 constructed of a non-heat conducting material, one end of the base 11 being slotted inwardly as at 12 to provide a recess for a metal plate 13. One longitudinal edge of the base 11 is provided with a concaved recess extending the full length thereof, the said recess being designated at 14. One end of the plate 13 extends beyond the recessed edge of the base and has pivotally connected thereto as at 15, a clamping bar 16, the body of the bar being enclosed within a rubber sleeve 17. The inner side of the rubber sleeve 17 coacts with the recessed edge 14 of the base to clamp the strand of hair therebetween, the two parts being held in clamped relation in a manner now to be explained. Pivoted to the free end of the bar 16 as at 18 is a pair of connecting links 19, the same being disposed in spaced parallel relation so as to fit opposite sides of the reduced end 20 of the base 11. The other end of the links 19 have pivoted thereto, one end of a cam lever 21, the pivoted end 22 of the said lever having a cam portion for interlocking engagement with a recess in the base 11. This particular construction of clamping means is old in the art so that a more detailed explanation of the same is not believed necessary. The features involving my invention will now be explained.

The outer edge of the plate 13 is formed with an upstanding flange 23, the said flange being disposed in spaced parallel relation with respect to the adjacent end of the base 11. A portion 5 of the flange 23 is cut away to provide a stop shoulder 24, the said shoulder being bent inwardly toward the adjacent end of the base 11 to be disposed on a plane inwardly of the inner face of the flange 23. The plate 13 is secured to the 10 base 11 by a rivet 25 which passes through the base and the metal plate 13.

Mounted in the flange 23 and adjacent wall of the base 11, is a pivot pin 26 on which the lower end of an anchor pin 27 is pivotally connected. The base end of the pin 27 is disposed in the path of the shoulder 24, the said shoulder limiting the movement of the pin 27 from a collapsed position against the plate 13 to a vertical upstanding position for the purpose to be here- 20 inafter explained.

In use of the hair clamp and scalp protector 10, the clamping lever 21 is released to enable the clamping bar 16 to be swung to an open position. The clamp 10 is applied to the scalp 25 end of a strand of hair A to be waved with the hair passing between the bar 16 and the adjacent side of the base 11. Thus by closing the clamp and securing the parts in clamped position by moving the cam lever 21 to the position 30 shown in Figure 1, the base of the strand of hair is tightly gripped. This strand of hair is now ready to be curled or wound upon the winding rod, and I have constructed a winding rod which is along the principle of that now in use 35 but which makes the same adaptable for use in association with the hair clamp 10 previously described.

The winding rod is designated in its entirety by the reference numeral 28, and includes a spool shaped member 29 having a kerf 30 in one end thereof. Fitting into the opposite end of the member 29 is a bearing member 31, the said bearing member being captively connected to the member 29 for permitting rotation of the member 29 relative to the bearing member and this movement is limited in turning in one direction only, that is, the member 29 is turnable in the direction of winding movement of the strand of hair A upon the rod 28. Turning movement of the member 29 relative to the bearing member 31 in one direction only is controlled by a ratchet mechanism 32 contained within the recessed end of the member 29. The bearing member 31 includes an extension 33 having cross slots 34 in 55 the outer face thereof. Pivoted to one end of the member 29 is a clasp 35, the cross sectional contour of which conforms to that of the member 29 so that the clasp 35 may be brought into clamping relation with respect to the member 29.

After the hair and scalp clamp 10 has been positioned in the manner hereinbefore explained, the operator places the free end of the strand of hair A between the clasp 35 and the member 29 and proceeds to swing the clasp in the clamp- 60 ing relation with respect to the member 29 and then starts the winding operation. The winding rod 28 is turned in the direction toward the base of the strand of hair A and when it reaches a point adjacent the base of the strand of hair, 65 the bearing member 31 is engaged with the pin 27, the pin 27 being seated in one of the slots 34. It will of course be understood that the pin 27 is swung from its normally collapsed position to an angular position such as shown in Figure 3 of the 70 drawing in dotted lines. The operator now in-

serts a key 36 into the kerf 30 to permit of the turning of the member 29 relative to the bearing member 31 in order that a tensional stretch may be imparted to the wound hair upon the winding rod. As the member 29 is turned by the manipulation of the key 36, the pin 27 moves upwardly to a vertical position where it is engaged by the stop shoulder 24, and continued turning of the key 36 imparts the necessary stretch to the hair. In the method now in use, it is the 10 practice to permit the winding rod to remain in bearings provided on the hair clamp and scalp protector but such practice leaves that portion 15 of the strand of hair between the scalp and the hair wound on the rod straight after the completion of the hair waving process. Therefore, it is a feature of my invention to remove the winding spindle with the hair wound thereon from direct connection with the hair clamp 10 and this is accomplished by withdrawing the slotted end 20 of the winding rod 28 from the pin 27 and manually moving the pin 27 to a collapsed position against the plate 13. The operator then proceeds to impart a further turning movement to the rod 28, causing the entire strand of hair 25 A to be wound on the spindle. The only portion of the strand not wound is that gripped by the clamp 10.

With the strand of hair A fully wound upon the winding rod 28, it is possible to slide the 30 permanent wave heater element B over the wound hair with the usual pad and wrapper C interposed between the wound hair and the heating element, as shown in Figure 4.

From the foregoing construction and method herein shown and described, it will be seen that the entire length of a strand of hair may be wound upon the curling rod subsequent to the application of heat and upon removal of the spindle 28 and clamp 10 from the strand of hair 40 a perfect curl extending the length of the strand will result.

While I have shown and described what I consider to be the most practical embodiment of my invention, I wish it to be understood that such changes and alterations as come within the scope of the appended claims may be resorted to if desired.

Having thus described the invention, what I claim as new and desire to secure by Letters 50 Patent, is:—

1. A hair clamping device for use in association with a hair curling rod including a relatively flat elongated base of heat resisting material, a metal plate embedded in one end of said base and projecting therebeyond, an upstanding flange at the outer edge of said plate in spaced relation to the adjacent end of said base, and a curling rod anchor pin pivotally mounted between said flange and adjacent end of said base for lateral swinging movement to an operative upstanding position to releasably receive one end of a curling rod, or to a collapsed out of the way position against said plate.

2. A hair clamping device for use in association 65 with a hair curling rod including a relatively flat elongated base of heat resisting material, a metal plate embedded in one end of said base and projecting therebeyond, an upstanding flange at the outer edge of said plate in spaced relation to the 70 adjacent end of said base, a curling rod anchor pin pivotally mounted between said flange and adjacent end of said base for lateral swinging movement to an operative upstanding position to releasably receive one end of a curling rod, or to 75

a collapsed out of the way position against said plate, and a stop shoulder provided on said flange in the path of upward swinging movement of said pin to limit the movement of said pin to upstanding position.

3. Hair waving apparatus comprising in combination, a hair clamping device for clamping engagement with the base end of a strand of hair to be curled, said hair clamping device including 10 a pair of coacting elongated jaw members pivotally connected at one of their ends, said jaw members being free of any curling rod bearings, a pin member pivotally mounted at one end of said hair clamping device for swinging movement transversely thereof, a hair curling rod including a spindle member about which hair to be curled is adapted to be wound, a bearing member rotatably mounted at one end of said spindle member and having crossed slots in the outer end thereof, 15 ratchet means operatively connecting said bearing member and spindle member together for turning movement relative to each other during a winding operation of said spindle member, said pin member adapted to be swung to a raised position relative to said clamping jaws when the 20 hair to be wound is substantially fully wound

upon said spindle member to be received in one of said crossed slots at one end of said curling rod to enable manual turning of the other end of said curling rod to effect a tensioning of the wound hair upon said curling rod, said curling rod being separable from said pin member when the wound hair is tensioned thereon by manually shifting said curling rod longitudinally with respect to said clamping device.

4. In hair waving apparatus, a hair clamping 10 device comprising in combination, a pair of flat elongated jaw members pivotally connected together at one of their ends, said jaw members being free of any upstanding curling rod bearings, releasable means at the other end of said jaw members for securing the same in closed position, a curling rod anchor pin pivoted to said hair clamping device at one end thereof, said anchor pin being so pivoted as to swing transversely with respect to said jaw members whereby the slotted 15 end of a hair curling rod may be operatively connected with said anchor pin or disconnected therefrom by shifting the curling rod longitudinally relative to said jaw members.
